HANDLE BOX

Aaron Berke, Brooklyn, N. Y.

Application August 20, 1937, Serial No. 160,115

10 Claims. (Cl. 229—52)

My invention relates to improvements in boxes, and more particularly to means in combination therewith for providing a handle therefor, and especially refers to collapsible paper boxes with handles.

In the accompanying drawing, I have illustrated in Fig. 1 in plan view, part of the blank of a paper box embodying an application of my invention. Fig. 2 is a top view of part of the box, 10 parts being broken away. Fig. 3 is a cross-section on the line 3—3 of Fig. 2. Fig. 4 a top view of the outer part of the box, and Fig. 5 a longitudinal section through the handle and top of the box.

15 The box may be of the conventional cloak and suit type, comprising inner and outer halves hinged at the bottom. The inner top portion 6 may be provided with a turned-under flap 7, having flaps 8, 9, scored and hinged at 10, 11, and 20 flaps 12, scored and hinged at 13. Beneath the inner top portion 6 may also be secured a reinforcing piece of card 14, perforated at 16, in register with the handle of inner top 6, to provide a two-ply handle 15 of double thickness. This 25 handle is preferably not cut entirely through or separated, small retaining pieces 17 remaining to hold the handle in place until used.

The outer top portion 18 of the box may be provided with a rectangular hole or opening 19, 30 through which the handle projects when in use, the same being covered by flap 25 hinged at 26, and slits 20 may also be provided in the top portion of the box for the hook-like flaps 21, which may be passed therethrough to hold the box in 35 closed position. The hook like flaps are tabs formed by cuts in the outer ply of the inner top portion 6 of the box, as shown in Fig. 1. These tabs are pulled into vertical position before the wall 18 of the outer part of the box is moved 40 into position over the wall 6 of the inner part of the box; and the tabs 21 are then bent down over wall 18 and pushed through the slits 20. The blanks may be stacked flat or in folded position until used.

45 When forming the box for use, the flap 7 is turned under the inner top portion 6, being hinged thereto along the score 22, this bringing the flaps 8, 9 immediately beneath the enlarged ends of the handle 15. By now pressing said ends 50 beyond the flaps 8, 9 at the same time breaking the small pieces 17, and drawing back on the handle, the lateral extensions of the handle ends extend laterally beyond the opening left by the flaps 12, thereby securely holding the handle in 55 position, and the center or bar of the handle may

now be passed through the opening 19 of the outer portion of the box, which slidably fits over the inner portion, and as an additional means for securing the box in closed position the hook-like flaps 21 may be passed through the slits 20, 5 and of course metal stitches 23 or any other suitable means may be employed to secure the turned-under portion 7 to the top portion 6 of the inner top portion of the box.

Of course it will be understood that various 10 modifications may be made in the construction and arrangement of parts without departing from the spirit of the invention, as claimed.

I claim:

1. A handle box of flexible sheet material, comprising a body, a portion of one wall of which is of two-ply construction, the outer of said plies having cut or stamped therein an enlarged-ended strap to serve as a handle for the box, and the inner of the plies being cut to permit the 20 handle ends to be pressed therethrough, and means on the inner ply for interlockment with the handle ends, to hold the handle to the box.

2. A handle box of flexible sheet material, comprising a body, a portion of one wall of which is of two-ply construction, the outer of said plies having cut or stamped therein an enlarged-ended strap to serve as a handle for the box, and the inner of the plies being cut to permit the handle 25 ends to be pressed therethrough and having slots 30 for interlockment with the handle ends and along which the handle ends may be forced toward each other to cause the handle to be protruded from the box surface for gripping purposes.

3. A handle box of flexible sheet material, comprising a body, a portion of one wall of which is of two-ply construction, the outer of said plies having incompletely severed therein an enlarged-ended strap to serve as a handle for the box, and the inner of said plies being cut to permit of passage therethrough of the handle ends, upon pressure sufficient completely to sever the attachment of the handle to the outer ply, and means on the inner ply for interlockment with the handle ends, 40 to hold the handle to the box.

4. A handle box of flexible sheet material, comprising a body, a portion of one wall of which is of two-ply construction, the outer of said plies having cut or stamped therein an enlarged-ended 50 strap to serve as a handle for the box, and the inner of the plies being slotted to form yieldable elements which permit the handle ends to be pressed therethrough, and which upon subsequent pull on the handle, interlock with the han- 55

dle ends and are held by the outer ply to hold the handle to the box.

5. A handle box of flexible sheet material, comprising an inner part, and an outer part, one of 5
the walls of the inner part being in two plies, one
ply whereof is a flap extension of the other ply,
folded against the inside thereof in the erection
of the box, the outer of said plies having cut or
10 stamped therein an enlarged-ended strap to serve
as a handle for the box, and the inner of said
plies being slotted to form yieldable elements
which permit of passage of the handle ends
through the inner ply, and which, upon subse-
15 quent pull on the handle, interlock with the han-
dle ends and are held by the outer ply, to hold
the handle to the box.

6. A handle box of flexible sheet material, comprising an inner part, and an outer part, one of 20
the walls of the inner part being in two plies, one
ply whereof is a flap extension of the other ply,
folded against the inside thereof in the erection
of the box, the outer of said plies having cut or
25 stamped therein an enlarged-ended strap to serve
as a handle for the box, and the inner of said
plies being cut out to permit passage there-
through of the handle ends, and means on the in-
ner ply for interlockment with the handle ends,
30 to hold the handle to the box.

7. A handle box of flexible sheet material, comprising an inner part, and an outer part, one of 35
the walls of the inner part being in two plies, one
ply whereof is a flap extension of the other ply,
folded against the inside thereof in the erection
of the box, the outer of said plies having cut or
35 stamped therein an enlarged-ended strap to serve
as a handle for the box, the inner of said plies be-
ing cut in registration with the handle-end cuts
in the outer ply, to permit the handle ends to be
pressed through the inner ply, and means on the
40 inner ply for interlockment with the handle ends,
thereupon to hold the handle to the box.

8. A handle box of flexible sheet material, comprising an inner part, and an outer part, one of 45
the walls of the inner part being in two plies, one
ply whereof is a flap extension of the other ply,
folded against the inside thereof in the erection
of the box, the outer of said plies having cut or

stamped therein an enlarged-ended strap to serve 5
as a handle for the box, and the inner of said
plies being cut to permit passage therethrough
of the handle ends, means on the inner ply for
interlockment with the handle ends, to hold the
10 handle to the box; the outer part of the box hav-
ing a wall adapted to overlie the handle-bearing
wall of the inner part of the box when the box is
closed, and having a slot therein in registration
with the strap portion of the handle, whereby
15 such strap portion may be drawn through the
slotted wall of the outer part of the box for hand
grip, after the handle ends have locked as aforesaid.

9. A handle box of flexible sheet material, comprising a body, a portion of one wall of which is 15
of two-ply construction, the outer of said plies
having cut or stamped therein an enlarged-ended
strap to serve as a handle for the box, and the
inner of the plies being cut to permit the handle
20 ends to be pressed therethrough, and means on
the inner ply for interlockment with the handle
ends, to hold the handle to the box; the outer ply,
at the part thereof from which the handle is to
be cut, having secured thereto a strip of reinforc-
25 ing material, whereby to give added strength to
handle as finally formed therefrom.

10. A handle box of flexible sheet material, comprising an inner part, and an outer part, a 30
portion of one wall of the inner part being of
two-ply construction, the outer of said plies hav-
ing cut or stamped therein an enlarged-ended
strap to serve as a handle for the box, and the
inner of the plies being cut to permit the handle
35 ends to be pressed therethrough, means on the
inner ply for interlockment with the handle ends,
to hold the handle to the box, and the outer part
of the box having a wall adapted to overlie the
handle-bearing wall of the inner part of the box
40 when the box is closed, and having a slot there-
in in registration with the strap portion of the
handle, whereby such strap portion may be drawn
through the said slot in the wall of the outer part
of the box, for hand grip, after the handle ends
45 have been locked as aforesaid.

AARON BERKE.
